UNITED STATES PATENT OFFICE.

JAY B. SMITH, OF GIRARD, ALABAMA, ASSIGNOR OF ONE-HALF TO JOHN L. BETTS, OF MUSCOGEE COUNTY, GEORGIA.

IMPLEMENT FOR PULLING NAILS, FENCE-WIRES, &c.

1,143,083.

Specification of Letters Patent. Patented June 15, 1915.

Application filed May 18, 1914. Serial No. 839,386.

To all whom it may concern:

Be it known that I, JAY B. SMITH, a citizen of the United States, residing at Girard, in the county of Russell and State of Alabama, have invented a new and useful Implement for Pulling Nails, Fence-Wires, &c., of which the following is a specification.

The present invention appertains to an improved implement or tool for pulling 10 nails, spikes, staples or the like, for stretching the strands of a wire fence or the like, for ripping up or loosening flooring boards, planks and the like, for moving trucks in the manner of a pinch bar, and for kindred 15 other purposes.

The invention has been illustrated in its preferred embodiment in the accompanying drawing, wherein:—

Figure 1 is a perspective view of the improved implement with the gripping and fulcrum members separated, a portion of the handle or lever being broken away. Fig. 2 is a plan view of the implement, showing the handle moved to bring the gripping and 25 fulcrum members together. Fig. 3 is a cross section taken on the line 3—3 of Fig. 2.

In carrying out the present invention, there is provided a handle or lever 1, of any suitable construction, and which is provided 30 at its lower end with an angularly-extending wedge-like portion 2 having its sides diverging downwardly, as will be clearly obvious by reference to the drawing. The wedge 2 is preferably somewhat circular in 35 outline, and is provided with a central transverse bore or opening 4 through which a transverse bolt or pivot member 5 is journaled. The implement also includes a pair of complementary or companion shoes 6, 40 constructed of suitable metal, and having their bottoms or treads straight or flat. The shoes 6, which provide the gripping and fulcrum members, are provided intermediate 45 their ends and flush with or adjacent their outer sides, with upstanding ears 7 disposed at the sides of the wedge 2.

The wedge 2 is pivoted or fulcrumed between the shoes 6, the end portions 8 of the bolt or fulcrum member 5 being preferably 50 non-circular in cross section and engaging loosely through non-circular apertures or openings 9 provided in the ears 7 of the shoes, whereby the shoes will oscillate with the fulcrum member 5 and in unison, while 55 the lower end of the handle or lever 1 is ful-

crumed or pivoted upon the member 5 between the shoes. The head 5^a of the bolt 5 seats against the outer side or face of one ear 7, while knurled nut 10 is threaded upon the tip of the bolt 5 and seats against the 60 outer side or face of the other ear 7 to maintain the shoes 6 in place. Attention is directed to the fact that the shoes 6, although they are constrained against oscillation or rotation upon the bolt 5, may slide longitudinally upon the bolt 5 whereby when the 65 nut 10 is tightened and loosened, the shoes may be drawn together snugly against the sides of the wedge 2, or may be permitted to separate, for the purpose which will here- 70 inafter appear.

In order to effectively fulcrum the handle or lever 1 between the shoes, and reduce the shearing strain upon the bolt 5 to a minimum, the sides of the wedge are provided 75 with bosses 3 surrounding the opening 4, and fitting within depressions or sockets 11 formed in the inner sides or faces of the shoes 6 and their ears 7.

The front ends of the shoes 6 are provided 80 with forwardly projecting toes or claws 12, which are flush with the bottoms or treads of the shoes, and which are relatively thin. The adjacent edges of the toes or claws 12 are beveled downwardly, as at 85 13, to provide the upper jaw or gripping edges 14 along the adjacent portions of the claws 12.

The rear ends of the shoes 6 are provided 90 with rearwardly projecting and upturned heel portions 15, which serve as fulcrums for the shoes, and which provide curved seats 16 for stops 17 provided upon the sides of the wedge 2 above the ears 7 of the shoes 6. The stops 17 are engageable with 95 the seats 16 when the handle or lever 1 is swung rearwardly and downwardly.

The wedge 2 is so arranged between the ears 7 of the shoes 6, that when the handle or lever 1 is swung approximately perpendicular with the shoes 6, or to an upstanding position when the shoes 6 are horizontal, the thickest portion of the wedge 2 will be moved in advance of the fulcrum member or bolt 5 between the forward portions of 105 the ears 7, and consequently, the jaws or claws 12 will be spread apart or opened, as seen in Fig. 1. Conversely, when the handle or lever 1 is swung rearwardly and downwardly, the thickest portion of the wedge 2 110

is arranged to swing between the rear portions of the ears 7, to thereby swing the heel portions 15 of the shoes apart, and to correspondingly swing the claws or jaws 12 together, as seen in Fig. 2. It will thus be apparent that when the handle or lever 1 is swung rearwardly and downwardly to bring the stops 17 into engagement with the heel portions 15, the claws or jaws 12 will be swung 10 toward each other into gripping relation, and the shoe will then be swung upon the upwardly curved heel portions 15 as fulcrums. It is to be noted that the wedge 2 extends angularly forward from the lower 15 end of the handle 1, and that the wedge is provided with a curved edge projecting between the treads of the shoes, as seen in Fig. 3, the shoe treads being disposed tangentially relative to the said curved edge of the 20 wedge. Thus when the lever or handle 1 is swung rearwardly, to bring the stops or lugs 17 into engagement with the heel portions 15 of the shoes, the curved edge of the wedge 2 will ride upon the surface, and the 25 rear portion of the wedge will provide a fulcrum coöperating with the fulcrums provided by the heel portions 15, in order that the shoes may be swung effectively. This will reduce the shearing strain upon the 30 lugs or stops 17, and will also assist materially in swinging the shoes for extracting the nail, or the like.

The present implement or tool may be employed for a variety of purposes, such

as, an extractor for nails, spikes, drift bolts, 35 staples, and the like, or a stretcher for fence wires, or a wrecking bar for prying up flooring boards, planks or the like, or a pinch bar for moving a truck or the like.

Having thus described the invention, what 40 is claimed as new is:—

An implement comprising a pair of shoes having flat treads, coöperating relatively thin gripping toes at their front ends, upstanding ears intermediate their ends, and upwardly curved heel portions at their rear ends; a pivot member engaged through the said ears; and a handle having a wedge extending angularly forward from its lower end and fulcrumed upon the said pivot member between and bearing against the said ears, the lever having a pair of side lugs above the said ears to seat against the heel portions when the lever is swung rearwardly, and the wedge having a curved 55 edge projecting between the treads of the shoes and forming a fulcrum arranged to ride upon the surface against which the treads of the shoes rest, when the lever is swung to bring the said lugs into engagement with the heel portions of the shoes. 60

In testimony that I claim the foregoing as my own, I have hereto affixed my signature in the presence of two witnesses.

JAY B. SMITH.
